(57) **CLAIM**

I claim the ornamental design for a jewelry setting, as shown.

DESCRIPTION

FIG. 1 is a left side elevational view of a jewelry setting showing my new design, the right side being identical; FIG. 2 is a front elevational view thereof, the rear being identical;

FIG. 3 is a top plan view thereof;

FIG. 4 is a bottom plan view thereof; and,

FIG. 5 is a perspective view thereof.

The subject matter shown in dashed lines, and any surfaces of the design not shown, including interior surfaces, form no part of the claimed invention.
